COMBINATION SEAT-CABINET AND TABLE

Julius Kupfer, Brooklyn, N. Y.

Application July 21, 1934, Serial No. 736,285

2 Claims. (Cl. 155—123)

This invention relates to a combination seat-cabinet and table, particularly of the type adapted for use in association with the seating structure of an automobile.

5 It is quite a common practice for automobile passengers to take along with them, on a motor trip, various items of food and other articles, and these are generally wrapped in packages and deposited on the seat or the floor of 10 the car. This is not only inconvenient in that these packages are space-consuming, and are an impediment to the comfort of the passengers seated in the car, but there is always the danger of such articles being subject to damage or injury unless held by one of the passengers. It is 15 hence one of the objects of my invention to enable articles of this class to be securely and immovably held in place by depositing them, in a preferred form of this invention, within the 20 back-rest portion of the front seat and in such a manner as to render them readily accessible for use, and yet not an obstruction to or in any way interfering with the comfort of the passengers seated in the rear of the car. And it 25 is still another object of my invention to permit its use without in any way affecting the spring cushioning means generally employed within the back rest of the front seat of the car.

30 Passengers also frequently desire to have the use of a table within the car, either for the purpose of serving of food, playing cards, etc. It is with the further purpose of providing such a need that I have conceived this invention, an 35 object which I accomplish by employing a table which normally, in its inoperative position, forms a part of the cabinet casing contained in the front seat in which the said articles are stored, and which can readily and easily be swung into 40 its horizontal operative position, the entire structure being of simple and inexpensive design.

Other objects, features and advantages will appear from the drawing and the description hereinafter given.

45 Referring to the drawing:

Figure 1 illustrates the interior of a car provided with my invention, and showing, in dotted lines, certain articles stored within the cabinet in its closed position.

50 Figure 2 is a perspective of the back-rest of the front seat, showing the cabinet open and the table in its operative position.

Figure 3 is a vertical cross section of the device constituting my invention, illustrating the 55 inner shelf in its raised position to permit the

withdrawal of articles contained within the cabinet, and further showing the table in its open position.

Figure 4 is a fragmentary plan view of Figure 3 taken along line 4—4, part of the inner shelf being broken away to show the contents therebelow.

Figure 5 is a fragmentary vertical section of a modification of my invention, showing a thermos bottle with a bead thereon supported by 10 a fixed shelf.

Figure 6 illustrates another modification of my invention showing how the table in its horizontal position is supported by an open door 15 therebelow.

In the drawing, the back-rest portion 10 of the front seat contains therein a cabinet formed by the concave wall 11 joining the lower wall 12 at the rear of the front seat, and the table 13 which in its closed position forms a closure for 20 said cabinet. The said table is supported preferably by flexible straps 14 which fold inwardly upon an upward swinging and closing of the said table, or what may also be termed the door, 13. Instead of the straps 14, hinged means may be 25 employed with similar effect.

Within the cabinet is the inner shelf 15 hinged to the wall 12 and swingable in a vertical direction, its lowermost horizontal position being fixed by the two brackets 16 upon which 30 the said inner shelf is adapted to rest. The said brackets extend inwardly within the cabinet, and are suitably secured to the walls thereof.

Contained within the lower portion or bottom compartment of the cabinet is the fixed shelf 35 17 which contains suitable apertures therein for the insertion of various articles, such as the thermos bottle 18 and the two articles 19 and 20, or other variously shaped and sized items, the roof of said compartment being the shelf 15 when 40 in its horizontal position. In this arrangement it will be noticed that these articles are adapted to rest upon the floor of the car and are held against lateral movement by the walls of the said apertures.

The said concave wall 11 extends upwardly and slopes rearwardly from the bottom of the front seat, thereby permitting the central portion of the back-rest 10 to contain the springs 21, 22 and 23 therein.

45 In the operation of this device, the table 13 is opened by swinging it downwardly, the inner shelf 15 is swung upwardly and the contents 18, 19 and 20 are inserted in place. The bottom compartment of the cabinet is closed by swinging 50 55

the said inner shelf 15 downwardly until it rests upon the brackets 16, and the table or door 13 swung upwardly to close the entire cabinet. The arrangement is such that the table 13, when brought into its vertical position and detachably locked in place by the spring latch 13a, is substantially flush with the rear wall of the back-rest,—there being no protruding elements whatsoever to inconvenience the passengers seated in the rear of the car. This device can be so dimensioned that sufficient space will be available for the housing of the articles desired to be stored within the cabinet. Inasmuch as the storage portion of the cabinet is at the bottom 15 of the back-rest 10, it is feasible to permit the wall 11 to slope rearwardly, the reduced space in the upper portion of the cabinet being sufficient to permit a withdrawal of the contents therefrom. The sloping arrangement of the wall 11 permits the use of springs 21, 22 and 23, as hereinabove stated, thereby enabling this device to function without affecting the usual spring cushioning means employed in a front automobile seat.

25 Should it be desired to use the table 13 for serving food thereon or for other purposes, this table is moved downwardly into its horizontal operative position as shown in Figures 2 and 3, the arrangement being such as to permit convenient access thereto by passengers seated in the rear of the car. It will be noticed that the inner shelf 15 is level with the table 13 thereby providing greater table area by utilizing a portion of the interior of the cabinet.

30 In the modification shown in Figure 5, the fixed shelf 24 is similar to shelf 17, containing apertures adapted to accommodate predetermined shaped and sized articles; but instead of permitting these articles to rest upon the floor of the car, the apertures in the shelf are so proportioned as to permit a protruding element of a stored article, such as the bead 25 of the thermos bottle, to rest upon the said partition 24.

35 Another modification is illustrated in Figure 6 which shows a bottom door 26 swung outwardly, and in such position serving as a support for the table 27 in its horizontal position. This arrangement enables the articles desired to be stored in the cabinet to be inserted through the doorway 50 rather than through the upper portion of the cabinet as is required in the above-described preferred form of my invention. With the use of the door 26 as the table supporting means, there is no necessity of employing straps 14 or other hinged devices from which the table may be suspended. The table 27 is held detachably locked in its vertical position by the spring latch 27a.

This invention is not limited to the specific forms herein described, as other modifications thereof can be employed and changes effected within the scope of the appended claims.

What I claim is:

1. In combination with an automobile seat, a cabinet within the upright back-rest portion of the seat, the front wall of the back rest being generally vertical, the forward wall of the upper portion of the cabinet being concave and sloping 10 rearwardly from the level of the seat to form an upwardly expanding space therebetween and the front wall of the back rest, a plurality of springs within said space and in abutting relationship with the forward wall of the cabinet and the 15 front wall of the back rest, a compartment at the bottom of said cabinet for the storage of articles therein, the rear wall of the cabinet containing an opening therein, a table pivotally supported on the rear wall of the cabinet and being 20 swingably movable rearwardly into a horizontal position and forwardly into a vertical position against said cabinet to form a closure over said opening, a shelf constituting the roof of the said compartment and pivotally attached to the front 25 wall of the cabinet and swingably movable in a vertical direction, means for detachably holding the table in its vertical position, and means for supporting said table and said shelf in their horizontal positions, the table and shelf in their said 30 horizontal positions being substantially in the same plane.

2. In combination with an automobile seat, a cabinet within the upright back-rest portion of the seat, the forward wall of the upper portion 35 of the cabinet sloping rearwardly from the level of the seat to form an upwardly expanding space therebetween and the front wall of the back-rest, yieldable cushioning means within said space and in operative engagement with the said front wall 40 of the back-rest, a compartment at the bottom of said cabinet for the storage of articles therein, the rear wall of the cabinet containing an opening therein, a table pivotally supported on the rear wall of the cabinet and being swingably 45 movable rearwardly into a horizontal position and forwardly into a vertical position against said cabinet to form a closure over said opening, a shelf constituting the roof of the said compartment and pivotally attached to the front wall of the cabinet and swingably movable in a vertical direction, means for detachably holding the table in its vertical position, and means for supporting 50 said table and said shelf in their horizontal positions, the table and shelf in their said horizontal positions being substantially in the same plane.

JULIUS KUPFER.
